US0D1113066S

(12) **United States Design Patent** (10) **Patent No.:** **US D1,113,066 S**
Enger et al. (45) **Date of Patent:** **** Feb. 10, 2026**

(54) **HOUSING FOR AN ELECTRIC VEHICLE
LOCKOUT DEVICE**

(71) Applicant: **Brady Worldwide, Inc.**, Milwaukee, WI (US)

(72) Inventors: **Andrew Enger**, Muskego, WI (US); **Gene Gladkov**, Muskego, WI (US)

(73) Assignee: **Brady Worldwide, Inc.**, Milwaukee, WI (US)

(**) Term: **15 Years**

(21) Appl. No.: **29/930,636**

(22) Filed: **Mar. 1, 2024**

(51) **LOC (15) Cl.** **13-03**

(52) **U.S. Cl.**

USPC **D13/110**; D13/133; D13/156

(58) **Field of Classification Search**

USPC D13/101, 103, 104, 107, 108, 110, 112, D13/118, 122, 146, 123, 124, 133, 154, D13/155, 156, 158, 162, 173, 178; 439/304, 310, 133, 135, 34, 35, 142, 144, 439/519, 521, 528, 638; D99/28, 99; D8/330, 331, 343, 346

(57) **CLAIM**

The ornamental design for a housing for an electric vehicle lockout device, as shown and described.

DESCRIPTION

FIG. 1 is a top, rear and right side isometric view of a housing for an electric vehicle lockout device showing our new design;

FIG. 2 is a top, front, and right side isometric view thereof; FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
